UNITED STATES PATENT OFFICE.

JOHN E. GARDNER, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed October 11, 1921. Serial No. 507,016.

To all whom it may concern:

Be it known that I, JOHN E. GARDNER, a subject of the King of Great Britain, and a resident of Chicago, Cook County, and State of Illinois, have invented certain new and useful Improvements in Automatic Telephone Systems, of which the following is a specification.

The present invention relates in general 10 to automatic telephone systems, and has for its principal object the provision of a new and improved trunking system for automatic exchanges.

In carrying out the above general object 15 of the invention a number of new features have been designed, the more important of which will be pointed out below.

One of the features of the invention is the provision of a new and improved combined 20 finder and connector switch which is adapted to operate either as a finder switch to hunt for and connect with the calling line or as a connector switch to connect with a called line. Linked with each of these combination switches is a secondary switch. This secondary switch is of a novel type 25 inasmuch as it is adapted to operate either as a secondary line switch when its associated combination switch is operating as a finder or as a finder when its associated switch is to be used as a connector.

Another feature of the invention is to 30 provide an improved starting circuit for these combination switches, whereby, in the normal operation of the system when these switches are operating as finder switches, only the combination switches whose associated secondary switches having their 35 wipers standing in engagement with an idle trunk line leading to a selector switch will be started. Means are also provided, so that if all of the combination switches are busy, due partly to their being used in setting up 40 connections and partly because their associated secondary switches are associated with busy trunk lines, the first idle one of 45 these combination switches is started and its linked secondary switch is caused to seek an idle trunk line.

A still further feature of the invention 50 is to provide means, whereby, while one of the combined switches is hunting as a finder

its associated switch may not be operated as a finder.

There are other features of the invention 55 not now specifically mentioned which, together with the foregoing, will be explained fully hereinafter with reference to the accompanying drawings.

As shown in the drawings, the invention 60 has been applied to a ten thousand line system, though, of course, the size of the system may be increased or decreased by the addition or elimination of selector switches 65 at the proper point in the trunking system.

Referring now to the drawings comprising 70 Figs. 1-6, inclusive, Figs. 1, 2, 3, and 4 show a circuit diagram of a complete connection between a calling substation A and a called substation A'. The apparatus involved in this connection includes a combination switch F, secondary switch C, first and second selectors E and E', secondary switch C' and combination switch F'. Fig. 5, shows the starting circuits diagrammatically of a group of the before mentioned combination switches. Fig. 6, shows the 75 general trunking layout of the system.

Referring now particularly to Fig. 1, there is shown a subscriber's substation A 80 of the well known automatic type having, in addition to the usual talking instrumentalities, a calling device S. The line of the substation terminates at the exchange in multiplied bank contacts accessible to a group of 85 combination switches, one of the latter being shown at F. In addition to the above the line of the substation A has associated with it a combined line and cut off relay 17.

The combined switch F is one of a group 90 of combination switches which have access to the line of the substation A. The switch F is of the usual Strowger vertical and rotary type having access to 100 subscribers' lines, there being 10 levels of bank contacts 95 with 10 subscribers' lines terminating in each level. The switch F differs slightly from the standard type in that, as under certain conditions it is adapted to operate as a finder switch, it is provided with a vertical bank having a bank contact for each level.

Inasmuch as the switches of the group such as F are adapted to be used either as

finder switches or connector switches, instead of having 10 finder switches and 10 connector switches, it is possible to handle the same amount of traffic with a lesser number of these combination switches. This is well understood because in a situation of this nature the traffic varies greatly, that is, while there may be more than 10 incoming calls to a group of 100 subscribers' lines, in all probability at the same time there will be only a few outgoing calls and vice versa. Thus it is possible by increasing the size of the group, as in the present case, to increase the traffic efficiency by providing a group of these combination switches which are used for either incoming or outgoing calls. Thus, in the present case, where ordinarily it would require 10 connector switches and 10 finder switches to handle the traffic of a group of 100 lines only about 15 of these combination switches are necessary to handle the same amount of traffic.

Associated with each of these combination switches is a secondary switch, the one associated with the combination switch F being shown in the drawings at C, Fig. 2. The secondary switch C is of the same general mechanical construction as that of the well known rotary line switches and has access to trunk lines extending to first selector switches and to other trunk lines terminating in the banks of second selector switches. Should it be found that the outgoing traffic from the group of combination switches exceed 10 calls at any one instant the secondary switch C will be given access to more than ten trunk lines extending to first selector switches and this may be as high as 15 in case there are times when there are 15 calls from the combination switches. On the other hand should there be a larger number of incoming calls than 10 at any given instant the rotary switch C will have access to a larger number of trunk lines terminating in the banks of the final selector switches. Depending upon the demands of traffic the rotary switch C is provided with more or less bank contacts and has access to a greater or less number of trunk lines extending to first selector switches or incoming from second selector switches. One of the outgoing trunk lines accessible to the secondary switch C is shown in the drawings terminating in the first selector E.

The first selector E is a switch of the usual vertical and rotary type and has access to trunk lines extending to second selector switches one of the latter being shown at E', Fig. 3.

The selector E' is similar to the selector E already described and has access to trunk lines terminating in the banks of secondary switches such as C'.

65 The equipment associated with one of

these trunk lines is shown in the drawings and comprises a combined line and cut off relay 312.

The secondary switch C' has associated with it the combination switch F'. The switches C' and F' are similar to the switches C and F already described and serve to illustrate the operation when the switch C' is used as a finder and the switch F' is used as a connector.

Fig. 5, shows the starting loop circuit of a group of 100 subscribers' lines, whereby the calling subscribers of the group control the starting of an idle combination switch as a finder.

Fig. 6, shows a general trunking diagram of a 10,000 line system which will now be referred to for a brief description of the manner in which a call is made from one subscriber to another. In order to describe this operation it will be assumed that the subscriber at substation A in the first thousand and group desires to call a subscriber at substation A' whose line is located in the fifth thousand. In order to do this the calling subscriber will remove his receiver and operate his calling device in accordance with the number assigned to the substation A'.

When the receiver is removed at substation A an idle combination switch such as F, whose associated secondary switch C is standing with its wipers in engagement with an idle trunk line extending to a first selector switch, is automatically operated to connect the calling line with the secondary switch C. The latter switch operates to extend the calling line to a first selector switch such as E. The calling subscriber may then call the first digit in the desired number which causes the first selector E to be raised to the proper level and to thereafter select an idle trunk line extending to a second selector switch. In the present case as the subscriber at substation A' is located in the first thousand the first selector E will be operated to the fifth level. In response to the next digit of the called number an idle second selector such as E' is operated to the desired level in order to select the proper group of combination switches which have access to the substation A'.

In the present case the substation A' is shown to be in the second hundred group of the fifth thousand. Therefore, the second digit called will be 2. As soon as the second selector E' has selected an idle trunk line extending to the desired group of combination switches an idle secondary switch such as C' is automatically operated as a finder to connect with the seized trunk line and extend it to its associated combination switch F'.

When the last two digits of the called substation are dialled by the calling subscriber the combination switch F' is operated as a connector switch to connect with the called line.

and to automatically signal the subscriber thereon. When the conversation is terminated the release of the connection takes place upon the calling subscriber replacing his receiver upon the switch hook.

Having briefly described the general method of establishing a connection with reference to the trunking diagram of Fig. 6, a detailed description of the circuit operation of the various switches will now be given. For this purpose it will be assumed, as before, that the subscriber at substation A in the first thousand desires to call the subscriber at substation A' in the fifth thousand. In order to do this the subscriber will remove his receiver and operate his sender S in accordance with the 4 digits which constitute the number of the substation A'.

When the receiver is removed at substation A a circuit is completed for the winding 15 of the relay 17 in series with the common relay 30, over the line conductors 11 and 12 in series. However, the coil 15 of the relay 17 only attracts the armature 21 and causes it to disengage its resting contact and engage its working contact and has no effect on its armatures 20 and 22. This operation is due to the peculiar construction of relay 17 which is so arranged that when the coil 15 is energized the armature is completely attracted against the core of this coil but when the coil 16 is energized the fulcrum of the armature is changed and the armature given a longer stroke so that it operates all springs. This construction is shown and described in detail in the co-pending application of M. L. Nelson, Serial No. 493,630, filed August 19, 1921. The relay 30 is common to 10 subscribers' lines, that is, all that are located in one level of the combination switches. By the operation of the armature 21 of the combined line and cut off relay 17 ground is disconnected from the multiple test contacts in the banks of the associated group of combination switches, thus rendering the line of the substation A selectable. The relay 30, upon energizing, at its armature 32 completes a circuit for starting the first idle combination switch as a finder which, we will assume, is the switch F. This circuit may be traced from ground by way of armature 32 and its front contact, conductor 38, armature 100 and its back contact, armature 81 and its back contact, and through the winding of the relay 58 to battery. Another result of the operation of armature 32 is that ground is disconnected from the vertical test contact 42 so as to enable the switch F to connect with the line of the substation A. Relay 58, upon energizing, at its armature 98 disconnects ground from the armature 107, at the front contact of this armature closes the circuit

of the slow acting release relay 60, at armature 97 prepares a locking circuit for itself, at armature 96 closes the circuit of the upper winding of relay 56, at armature 95 prepares the vertical testing circuit, at armature 93 transfers the test wiper 152 into operative relation with the switch F, thus disconnecting the test wiper 151, and at armature 92 prepares the circuit of the relay 62. The slow acting relay 60, upon operating, at its armature 106 opens a point in the release circuit, at its armature 105 places ground upon the release trunk conductor 162, and at armature 104 opens a point in the circuit of the relay 51. Relay 56, upon energizing, at armature 86 prepares a point in the locking circuit of the rotary test relay 52, at armature 85 prepares the rotary testing circuit, and at armature 84 opens a point in the circuit of the relay 51. As the combination switch is now in normal position the vertical test wiper 154 is associated with the vertical test contact 40 which is permanently grounded. A circuit is now completed which extends from the grounded contact 40, vertical test wiper 154, back contact and armature 68, armature 121 and its back contact, armature 95 and its front contact, and through the winding of the vertical test relay 57 to battery. Relay 57 is immediately energized over this circuit and, upon operating, at its armature 89 establishes a locking circuit for itself and at its armature 90 sends an impulse of current over the following path: Ground by way of front contact and armature 90, off-normal springs 124 and 123, through the winding of the slow acting relay 54, and thence through the winding of the vertical magnet 116 to battery. Magnet 116 operates to raise the switch wipers 150-154, inclusive, one step and at its armature 121 opens the locking circuit of the test relay 57, which deenergizes opening the circuit of the vertical magnet 116 which deenergizes also. If the calling subscriber's line is not located in the first level there will be a ground potential upon the test contact 41 and the vertical test relay 57 will be again energized and will operate in the same manner as before described to complete the circuit of the vertical magnet 116. The vertical magnet 116 operates to raise the switch wipers opposite the next level of bank contacts and to break the locking circuit of the test relay 57. The alternate operation of the test relay 57 and the vertical magnet 116 will continue until the switch wipers are raised opposite the level of bank contacts in which is terminated the contact set associated with the substation A. In the present case the substation A is located in the second level, therefore, immediately upon the switch wipers being brought opposite the second level there will be no ground

potential present upon the test contact 42, the vertical test relay 57 will not be energized and the vertical operation of the switch will cease. The slow acting relay 54 is energized in series with the vertical magnet 116 and maintains its armature attracted throughout the vertical movement of the switch. Relay 54, upon operating, at its armature 79 maintains the continuity of the vertical magnet circuit, as upon the first vertical step of the switch shaft the off-normal springs are shifted and the circuit of the vertical magnet includes the off-normal springs 124 and 125 and armature 15 79 and its front contact, and at armature 78 closes the circuit of the rotary test relay 52. Relay 52, upon operating, at armature 72 establishes a locking circuit for itself and at armature 73 prepares a point in the circuit of the rotary magnet 115. Upon the termination of the vertical movement of the switch the slow acting relay 54 deenergizes and the rotary magnet 115 is energized over a circuit extending from ground on release 20 trunk conductor 82, armature 85 and its front contact, armature 78 and its back contact, armature 73 and its front contact, through the winding of the slow acting relay 53, back contact and armature 69, and through the winding of the rotary magnet 115 to battery. The rotary magnet 115 is operated over this circuit and advances the switch wipers 150-153, inclusive, into engagement with the first set of bank contacts 35 in the second level and at armature 120 opens the locking circuit of the relay 52, which deenergizes opening the circuit of the rotary magnet which deenergizes also. The slow acting relay 53 is energized in series with the rotary magnet 115 and operates at its armature 74 to connect the test wiper 152 to the test relay 52. If the line of the calling substation A is not associated with the first set of bank contacts there will be a ground potential present upon the test contact engaged by the test wiper 152 and the test relay 52 will be energized. Relay 52, upon operating, at its armature 72 establishes a locking circuit for itself and at its armature 73 completes the circuit of the rotary magnet 115. Magnet 115 operates to rotate the switch wipers another step into engagement with the next set of bank contacts and at armature 120 opens the locking circuit of the test relay 52. The alternate operation of the test relay 52 and the rotary magnet 115 continues until the switch wipers 150-153, inclusive, are rotated into engagement with the set of bank contacts associated with the calling line which, we will assume, are the bank contacts 25-28, inclusive. When this occurs there will be no ground connected to the test contact 27, no circuit will be completed for the test relay 52 and the rotation of the switch will

cease. Then, following the deenergization of the slow acting relay 53, a circuit is completed which may be traced from ground on release trunk conductor 82, armature 72 and its back contact, through the lower winding of the switching relay 50, back contact and armature 74, front contact and armature 93, test wiper 152, test contact 27, armature 21 and its front contact, and through the winding of the coil 16 of the combination line and cut off relay 17 to battery. The cut off coil 16 and the switching relay 50 are immediately energized over this circuit. The coil 16, upon energizing, at its armatures 20 and 22 disconnects the line 80 relay 15 from the calling line and at the same time opens the circuit of the common relay 30. The coil 15 immediately deenergizes but the armature 21 remains attracted by the action of the coil 16. 85

In the combination switch F, relay 50, upon operating, at its armature 67 establishes a locking circuit for itself, at armature 69 opens a point in the circuit of the rotary magnet 115, at armature 68 opens a point in the vertical testing circuit, at armature 66 connects the release trunk conductor 162 to the release trunk conductor 82, and at armature 65 places direct ground upon the test contact 27 thereby completing a holding circuit for the cut off coil 16. A branch of this holding circuit also extends to the multiple test contacts 27 in the entire group of banks of the combination switches so that the line of the substation A can not be connected to while the present call is in progress. 95

It will be remembered that as soon as the combination switch F was seized ground was placed upon the release trunk conductor 162. By this operation a circuit is completed for the line relay 175 of the secondary switch C. This ground also places a short circuit around the relay 176 for a purpose which will appear fully later. Upon operating, relay 175 at armature 185 completes a circuit which includes the switching relay 178 and the motor magnet 179 in series, at its armature 186 disconnects the test wiper 206 from the conductor 161 and connects the said test wiper to a point midway between the switching relay and the motor magnet 179. In the normal operation of the system the secondary switch C is standing with its wipers in engagement with an idle trunk line otherwise its associated combination switch F would not have been started. It will be assumed that this trunk line is the one shown in the drawings terminating in the bank contacts 209-212, inclusive. Then, immediately upon the energization of the line relay 175 the switching relay 178 is energized. Relay 178, upon operating, at its armature 197 opens a point of the circuit of the line relay 175, at the front contact 110 120 125 130

of this armature establishes a locking circuit for itself, at armature 199 connects ground to the test contact 210 of the seized trunk line in order to busy it, at armature 198 extends the incoming starter wire 201 to the next idle secondary switch and at armatures 196 and 200 connects the trunk conductors 160 and 163 of the selected trunk line through the windings of the line relay 225 of the selector E.

Returning now to the operation of the combination switch F, when the relay 50 energizes a circuit is completed for the relay 62 at armature 67. The latter relay, 15 upon operating, at its armature 111 opens the circuit of the slow acting relay 60, at its armature 112 opens a point in the circuit of relay 51, at armature 113 establishes a locking circuit for the relay 58 independent 20 of springs controlled by relay 51, at armature 109 closes the circuit of the relay 51, and at armatures 108 and 110 connects the line of the substation A to the trunk conductors 160 and 163. As was mentioned 25 before, line relay 225 of the first selector E is connected to the trunk conductors 160 and 163. Thus the subscriber's line is extended to the line relay 225. The relay 51, upon energizing, at its armature 71 closes a point 30 in a certain chain circuit the purpose of which will be explained later, at armature 80 extends the auxiliary starting wire on to the next idle combination switch, at armature 81 opens the original energizing circuit 35 of relay 58, and at the front contact of this armature extends the incoming starter wire to the next idle combination switch.

When the calling line is extended to the 40 selector E as above described, the line relay 225 is immediately energized over the calling line loop and operated to complete the circuit of the slow acting relay 226. Upon operating, the latter relay at armature 45 235 prepares the operating circuits of the selector E and at armature 234 places ground upon the release trunk conductor 213 thereby establishing a holding circuit for the switches C and F. This holding circuit may be traced from ground on the 50 release trunk conductor 213, test contact 210, test wiper 206, back contact and armature 194, armature 199 and its front contact through the winding of the switching relay 55 178 and thence through the winding of the rotary magnet 179 to battery. A branch of this holding circuit extends by way of release trunk conductor 162, front contact and armature 66 to release trunk conductor 82. 60 This holding circuit serves to maintain the secondary switch C and the combination switch F in their operated position. It will be understood that this holding circuit is completed before the slow acting relay 60

in the combination switch F has had time 65 to deenergize.

It will be noted that the circuit of the line relay 225 includes the secondary winding of the transformer of the dial tone machine T. In this manner an audible signal 70 is given to the calling subscriber in order to notify him that he may now operate his calling device. When the calling device is operated for the first digit of the desired called subscriber's number a series of interruptions 75 is produced in the line relay 225 which retracts its armature a plurality of times in response thereto. At each retraction of its armature 233 an impulse of current is sent to the vertical magnet 246 in series with 80 the slow acting relay 227. Magnet 246 operates to raise the switch wipers 250-252, inclusive, step by step until they are placed opposite the level of bank contacts corresponding to the digit dialled, which in this 85 case is the digit 5 as the called substation A' is located in the fifth thousand. The slow acting relay 227 is energized in series with the vertical magnet and upon the first vertical step of the switch shaft when the off-normal springs are operated completes a circuit at its armature 236 which extends from ground on release trunk conductor 213, armature 236 and its front contact, off-normal spring 244 and its working contact, and 90 through the winding of the stepping relay 228 to battery. Upon operating, relay 228 at its armature 237 establishes a locking circuit for itself, and at its armature 238 prepares the circuit of the rotary magnet 248. 95 Shortly after the termination of the vertical movement of the switch, the slow acting relay 227 deenergizes and completes the circuit of the rotary magnet 248. Magnet 248 operates to rotate the switch wipers one 100 step into engagement with the first set of contacts in the selected level and at its armature 243 opens the locking circuit of stepping relay 228, which deenergizes opening the circuit of the rotary magnet which deenergizes also. The further operation of the selector E depends upon whether its wipers are associated with an idle trunk line or not. Assuming that the associated trunk line is 105 busy, there will be a ground potential present upon the test contact engaged by the test wiper 251 and the stepping relay 228 will be again energized. Relay 228, upon operating, establishes a locking circuit for itself at armature 237 and at armature 238 completes the circuit of the rotary magnet. Magnet 248 operates as before to rotate the switch wipers another step into engagement with the next set of bank contacts in the selected level and at armature 243 opens the 110 locking circuit of the stepping relay 228. The relay 228 and the rotary magnet continue to operate alternately as long as the 115 120 125

switch wipers 250-252, inclusive, are associated with a busy trunk line. It will be assumed that the trunk line shown in the drawings terminating in the bank contacts 255-257, inclusive, is the first idle trunk line in the selected level. Under these conditions as soon as the switch wipers of the selector E are rotated into engagement with this set of bank contacts, the switching relay 229 is energized in series with interrupter relay 228 as the former relay is no longer short circuited, there being no ground potential present upon the test contact 256. Relay 229, upon energizing, at its armature 240 connects ground to the test contact 256 in order to prevent the selected trunk line being seized by another selector switch, at its armature 241 opens the circuit of the slow acting relay 226, and at armatures 239 and 242 extends the incoming trunk lines to the line relay 275 of the second selector E'.

The relay 275 of the selector E' is energized over the calling subscriber's line loop and at its lower armature closes the circuit of the slow acting relay 278. The latter relay operates at its lower armature to prepare the impulsing circuits of the selector E' and at its upper armature places ground upon the release trunk conductor 261 thereby establishing a holding circuit for the selector E, secondary switch C and combination switch F. This holding circuit may be traced from ground on release trunk conductor 261, test contact 256, test wiper 251, armature 240 and its front contact, through the winding of the switching relay 229, armature 243 and its back contact off-normal spring 244 and its working contact, and through the winding of the stepping relay 228 to battery. It will be noted that this holding circuit applies ground to the release trunk conductor 213 whereby the secondary switch C and combination switch F are also maintained in their operated positions over the previously traced holding circuit. It will be understood that this holding circuit is completed before the slow acting relay 226 in the selector E has had time to de-energize.

The calling subscriber may now operate his calling device in accordance with the second digit in the desired number. By this operation the circuit of the line relay 275 of the second selector E' will be opened a plurality of times in response to the interruptions in its circuit. The relay 275 retracts its armatures a plurality of times thereby sending impulses of current to the vertical magnet 282 in series with the slow acting relay 279. In response to this series of impulses the selector E' is stepped into the proper level and it is automatically operated to seek an idle trunk line therein. When an idle trunk line is found, which we will assume, is the trunk line terminating in bank

contacts 301-303, inclusive, the rotation of the selector E' is terminated and the switching relay 281 is energized in series with stepping relay 280. The relay 281, upon energizing, extends the incoming trunk conductors to the line coil 310 of the combined line and cut off relay 312 associated with the selected trunk line. The foregoing operations of the selector E' have all occurred in response to the second digit of the desired number and take place in a manner similar to the operation of the first selector E.

The line coil 310 of the relay 312 is immediately energized over the calling subscriber's line loop in series with the common relay 320. The coil 310, upon energizing, operates the armature 324 thereby disconnecting ground from the test contact 327 associated with the selected trunk line in the banks of the secondary switches and rendering it selectable. Another result of the energization of the line coil 310 is that the armature 316 is operated into engagement with its working contact. The springs 318 do not open at this time nor is the working contact of 316 brought into engagement with the contact 319. By the operation of armature 316 ground is placed upon the test contact 302 and a holding circuit is established for the selector E' and the previously operated switches.

The relay 320 is common to a number of these trunk lines which may be more or less in number depending upon the number of simultaneous calls that can be set up. In the present case, it has been assumed, that the incoming traffic to the group of lines in which is located the substation A' is somewhat in excess of the outgoing calls from this group and, under certain conditions, all the combination switches having access to the substation A' may be operated as connector switches. Under these conditions there will be 15 incoming trunk lines from the banks of second selector switches accessible to the secondary switch C'. In a group as large as this there would be possibly 5 relays such as 320, that is, the relay 320 would be common to 3 trunk lines.

Relay 320, upon energizing, at its armature 321 places ground upon the starting wire 323 thereby completing a circuit for starting the first idle secondary switch which we will assume, is the secondary switch C' associated with the combination switch F'. This starting circuit may be traced from the grounded starter wire 323, armature 342 and its back contact, through the winding of the slow acting relay 337, and through the resistance 357 to battery. The relay 337, at its armature 355 places ground upon the release trunk conductor 373, at its armature 351 opens a point in its short circuiting circuit and also the circuit of relay 338, and at its armature 353 completes the circuit of the

relay 336. Relay 336, upon operating, at its armature 348 brings the test wiper 367 into operative relation with secondary switch C' at the same time disconnecting the test wiper 366, at armature 347 prepares a locking circuit for itself, at armature 350 completes a circuit which includes the switching relay 335 and the motor magnet 339 in series, and at its armature 349 connects the test wiper 367 to the latter circuit at a point midway between the switching relay and the said motor magnet. The operation of the secondary switch C' now depends upon whether its wipers 365-368, inclusive, are associated with the bank contacts of the selected trunk line. If not, there will be a ground potential upon the test contact engaged by the test wiper 367 switching relay 335 will be short circuited and the motor magnet 339 being supplied with direct ground by way of the said test wiper will operate as a buzzer to advance the switch wipers step by step in search of the trunk line in use. When the switch wipers engage the bank contacts of the selected trunk line which, we will assume, are the bank contacts 325-328, inclusive, there will be no ground potential present upon the test contact 327 and the switching relay 335, being no longer short circuited, is energized in series with the motor magnet 339. Relay 335, upon energizing, at its armature 343 connects ground to the test contact 327, at this same armature establishes a locking circuit for the relay 336 opens the circuit of the slow acting line relay 337 at armature 342, at the front contact of this armature partially extends the starter wire to the next idle secondary switch, at armature 341 prepares a point in its locking circuit and at armatures 340 and 345 extends the trunk line in use to the line relay 381 of the combination switch F'. The incoming starter wire 323 is completely extended to the next idle secondary switch upon the deenergization of the slow acting relay 337.

When ground is placed upon the test contact 327 the cut off coil 311 of the combined line and cut off relay 312, immediately energizes. The coil 311, upon operating, completely attracts all the armatures of the relay 312. By the operation of armatures 315 and 317 the line coil 310 is disconnected from the trunk conductors and the circuit of the common relay 320 is opened. The armature 316 is completely attracted so that the springs 318 are opened and the working contact of armature 316 is forced into engagement with the spring 319. The springs 318 are so adjusted that they do not open until the working contact of armature 316 is forced into engagement with the spring 319. The provision is made so that the holding circuit of the previously operated switches will be maintained continuously. The two

step operation of the relay 312 is due to its mechanical construction as it is constructed in the same manner as the relay 17, which has been described hereinbefore.

It will be remembered that the line relay 337 of the secondary switch C', upon operating, places ground upon the conductor 373 which extends by way of back contact and armature 397, back contact and armature 402, and through the winding of the relay 391 in the combination switch F' to battery. The relay 391 is immediately energized and operates at its armature 413 to extend the incoming starter wire 457 to the next idle combination switch, at armature 412 extends the auxiliary incoming starter wire to the next idle combination switch, and at its armature 439 completes a point in a certain chain circuit the purpose of which will be described later. The relay 391 is energized at this time so that the combination switch F' may not be started as a finder and to extend the starter circuit to an idle combination switch which may be operated as a finder.

Referring now to the operation of the combination switch F' when the calling subscriber's line is extended to the line relay 381, this latter relay is immediately energized over the calling line and at its armature 400 completes the circuit of the slow acting relay 382. The latter relay, upon operating, at its armature 404 prepares the impulsing circuits of the combination switch F', at its armature 403 places ground upon the release trunk conductor 373 and at its armature 402 completes another circuit for the slow acting relay 391 to prevent its circuit being broken by the deenergization of the slow acting relay 337 in the secondary switch C'.

When ground is placed upon the release trunk conductor 373 a holding circuit is established which extends by way of the conductor 373 armature 341 and its front contact, through the winding of the switching relay 335 of the secondary switch C' and through the winding of the motor magnet 339 to battery. A branch of this holding circuit also extends by way of front contact and armature 343, armature 348 and its front contact, wiper 367, bank contact 327, through the winding of the cut off coil 311 of the relay 312 to battery and also to the bank contact 302. From the bank contact 302 the holding circuit for the switches E', E, C, and F is the same as previously traced. In this manner all the switches are held in their operated positions.

The calling subscriber may now operate his calling device in accordance with the third digit of his desired number. A series of interruptions is thereby produced in the circuit of the line relay 381 which retracts its armatures a corresponding number of

times. At the first retraction of its armature 400 an impulse of current is sent over the following circuit: Ground by way of armature 415 and its back contact, armature 400 and its back contact, armature 404 and its front contact, off-normal springs 408 and 417, through the winding of the slow acting low resistance relay 388 and thence through the winding of the vertical magnet 451 to battery. The above is the circuit over which the first impulse to the vertical magnet is sent. Upon the first vertical step of the switch shaft the off-normal springs are shifted and the remaining vertical magnet impulses traverse a different circuit which is the same as the one previously traced except that it includes the off-normal springs 408 and 407 and armature 430 and its front contact, relay 388 being now in an operated position. Magnet 451 operates to raise the switch wipers 490-493, inclusive, step by step until they are raised opposite the desired level of bank contacts in which is terminated the contact set associated with the line of the substation A'. The slow acting relay 388, which is energized in series with the vertical magnet 451, maintains its armature attracted throughout the vertical movement of the switch and at the termination thereof deenergizes and transfers the impulsive circuit to the rotary magnet 452.

The calling subscriber may now operate his calling device for the next and final digit of his desired number. As before, another series of interruptions is produced in the line circuit of the line relay 381 which retracts its armature a corresponding number of times. At each deenergization of the line relay 381, a circuit is completed which extends from ground, by way of armature 415 and its back contact, armature 400 and its back contact, armature 404 and its front contact, off-normal springs 408 and 407, armature 430 and its back contact, normally closed springs controlled by armature 438 through the winding of the slow acting relay 389, back contact and armature 444, and through the winding of the rotary magnet 452 to battery. Magnet 452 operates to rotate the switch wipers into engagement with the set of bank contacts associated with the line of the called substation which, we will assume, are the bank contacts 495-498, inclusive, associated with the line of the substation A'. The slow acting relay 389 is energized in series with the rotary magnet 452 and operates at its armature 433 to short circuit the normally closed springs controlled by armature 438 of the test relay 390 so as to provide against premature opening of the rotary magnet circuit while the switch wipers are rotated over busy lines and at armature 432 connects the test wiper 491 to the test relay 390. The operation of the

combination switch F' now depends upon whether the substation A' is busy or not.

Assuming that the desired line is busy, there will be a ground potential on the test contact 496 and the test relay 390 is immediately energized. Relay 390, upon energizing, at its armature 438 opens the rotary magnet circuit, at armature 437 prepares a point in its locking circuit which is completed immediately upon the deenergization of the slow acting relay 389 and at armature 411 connects a lead from the busy machine to the lower heavy talking conductor. By this latter operation the calling subscriber is given the usual audible busy signal in order to inform him that the called line is inaccessible at the present time. Upon hearing this signal the calling subscriber will replace his receiver upon the switch hook thereby initiating the release of the operating switches in a manner which will be described later.

It will now be assumed that the line of the substation A' is idle when the switch wipers of the combination switch F' are rotated into engagement therewith. Under these conditions there will be no ground connected to the test contact 496 and no circuit will be completed for the test relay 390. Then, following the deenergization of the slow acting relay 389, a circuit is completed which extends from ground on conductor 375, armature 437 and its back contact, lower winding of the switching relay 392, back contact and armature 432, normally closed springs controlled by armature 410, test wiper 491, test contact 496, and through the winding of the cut off coil 501 of the combined line and cut off relay 502 associated with the substation A' to battery. The switching relay 392 and the cut off coil 501 are immediately operated over this circuit. The coil 501, upon energizing, disconnects the line of the called substation A' from its normal battery and ground connection in the usual manner.

In the combination switch F', the relay 392, upon energizing, at its armature 442 establishes a locking circuit for itself, at its armature 440 places direct ground upon the test contact 496, at its armature 444 opens the circuit of the rotary magnet 452, at the front contact of this armature and at armature 445 completes the signalling circuit of the called substation. Ringing current is now intermittently projected out over the called line until the subscriber at substation A' removes his receiver.

When the receiver is removed at substation A' the ring cut off relay 387 is immediately energized. Relay 387, upon energizing, at armature 426 establishes a locking circuit for itself, at armature 428 places the ground upon the conductor extending to the

front contact of armature 402 so as to provide against the deenergization of relay 391 upon the energization of the back bridge relay 386, at armatures 425 and 427 opens 5 the ringing circuit and at the front contacts of these armatures finally completes the talking connection. The back bridge relay 386 is immediately energized over the called subscriber's line and serves to supply talking 10 battery to the called subscriber. The calling subscriber is supplied with talking battery from the winding of the line relay 381.

When the conversation is terminated both 15 subscribers will replace their receivers upon their respective switch hooks. When the receiver is replaced at the calling substation the circuit of the line relay 381 is opened and this relay deenergizes and opens the circuit of its associated slow acting release relay 20 382. The latter relay, upon deenergizing, at armature 404 completes the circuit of the release magnet 450 of the combination switch F', at armature 403 removes ground from the release trunk conductor 25 373, and at armature 402 opens the circuit of the relay 391. Magnet 450 operates to restore the combination switch F' to normal. The deenergization of relay 382 also removes ground from the conductor 375 30 whereby the locking circuit of the ring cut off relay 387 and the switching relay 392 are opened and these relays deenergize. The deenergization of the slow acting relay 391 again connects the incoming starter wires to 35 the combination switch F'.

When ground is removed from the release 40 trunk conductor 373 the circuits of the relays 335 and 336 in the secondary switch C' are opened and also the circuit of the 45 cut off coil 311 in the trunk circuit. The relays 335 and 336, on deenergizing, restore the circuits of the secondary switch C' to normal. The deenergization of the cut off coil 311 restores the connection of the 50 line coil 310 with the trunk conductors. The holding circuit of the switching relays 281 and 229 of the selectors E' and E are also opened by the removal of ground from the release trunk conductor 373 and these relays deenergize thereby completing the circuits 55 of their respective release magnets 283 and 245. In this manner the selectors E and E' are released.

By the removal of ground from release 60 trunk conductor 213 the holding circuit of the switching relay 178 in the secondary switch C and the relays 50, 62, and 58 in the combination switch F' are opened. The deenergization of the relay 178 serves to restore 65 the circuit connections of the secondary switch C to normal. By the deenergization of the relays 50, 58 and 62 the circuit of the release magnet 117 of the combination switch F is completed and also certain 70 other circuits in this switch are restored to

normal. By the operation of the release magnet 117 the combination switch F is released.

The removal of ground from the release 75 trunk conductor 213 also opens the circuit of the cut off coil 16 of the combined line and cut off relay 17 whereby the line coil 15 is again connected to the line of the substation A. In the above manner the release 80 of the connection takes place upon the calling subscriber replacing his receiver upon the switch hook.

Having described the manner in which a 85 connection is set up between two subscribers certain special provisions and circuit arrangement will now be noted and explained.

It will be remembered that when the combination switch F was operated as a finder that the test wiper 152 was brought into operative relation with the switch and the 90 test wiper 151 disconnected. This provision is made so that there will be interference when the switch F is operated as a finder and when it is operated as a connector.

It will now be in order to explain how the 95 various combination switches are prevented from being operated as finders while their associated secondary switches are standing with their wipers associated with busy trunk lines. In order to describe this operation, it 100 will be assumed that when the calling subscriber at substation A removes his receiver that the combination switch F is idle and that its associated secondary switch C has its wipers standing in engagement with a busy trunk line. Under these conditions 105 there will be a ground potential present upon the test contact engaged by the test wiper 206. A circuit is now completed extending from the grounded test contact, test wiper 206, back contact and armature 194, 110 armature 199 and its back contact, armature 195 and its back contact, armature 186 and its back contact, conductor 161 and thence through the winding of the relay 59 in the switch F to battery. The relay 59 is energized over this circuit and, upon operating, completes a point in a certain chain circuit, which will be described later, at armature 99, and at armature 100 disconnects the 115 incoming starter wire 38 from the combination switch F and extends it by way of the conductor 44 to the next idle combination switch. Thus, when the calling subscriber removes his receiver, the combination switch 120 F will not be started as the starter wire has been disconnected from this switch and extended on. It will be noted that the energization of the relay 59 has no effect upon the auxiliary starter wire 40' which still remains connected to the switch F.

When all the combination switches of the group are busy either for the reason of their being used in connections or because their 125 associated switches are standing in engage- 130

ment with a busy trunk line means must be provided so that any combination switch may be started as a finder which is not being used in a connection regardless of whether or not its secondary switch is associated with a busy trunk line. In order to do this, when all the combination switches become busy for the reasons stated above, the aforementioned chain circuit is completed and the 10 relays 140 and 141 which are common to the group of combination switches are energized. The operation of these relays extends the incoming starter wire from the relays such as 30 to the auxiliary starting loop circuit. This operation may best be seen from the Fig. 5. In this figure it will be seen that when the relays 140 and 141 energize 15 all the incoming starter wires are disconnected from the usual starting loop and are extended to the auxiliary starting loop which is shown on the right of the figure. It will be noted that the ordinary starting loop circuit is controlled by two relays in each of the combination switches, the relays 20 51 and 59 in the combination switch F for example. This loop is so arranged that the incoming starter wire is extended either when the combination switch becomes busy or because its secondary switch is not associated 25 with an idle trunk line by the relay 51 in the former case and the relay 59 in the latter case. The auxiliary starting circuit is only under the control of armatures on the relays such as 51 in the combination 30 switches so that when this starting loop circuit is in use any combination switch may be started as long as it is idle regardless of whether its secondary switch is associated with an idle trunk line or not.

When one of the combination switches is started whose associated secondary switch is standing with its wipers in engagement with a busy trunk line its secondary switch is caused to hunt for and connect with an idle 35 trunk line. In order to describe this operation it will be assumed that the combination switch F is started over the auxiliary starting loop and that the switch C has its wipers associated with a busy trunk line. It 40 will be remembered that when the switch F is started ground is placed upon release trunk conductor 162 by the operation of the slow acting relay 60. This causes the energization of the line relay 175 of the secondary switch C. Relay 175, upon energizing, at its armature 185 completes a circuit which includes the switching relay 178 and the motor magnet 179 in series, at its armature 186 disconnects the test wiper 206 from the conductor 161 and at the front contact 45 of this armature connects the said test wiper to a point midway between the switching relay and the said motor magnet. As the 50 switch wipers of the secondary switches are

standing in engagement with a busy trunk 65 line, there will be a ground potential present upon the test contact engaged by the test wiper 206, the motor magnet 175 being supplied with direct ground by way of the said test wiper will operate as a buzzer to advance the switch wipers step by step in search of an idle trunk line. When the idle trunk line is found, there will be no ground potential on the test contact engaged by the test wiper 206, the switching relay 178, 70 being no longer short circuited, is energized in series with the said motor magnet. The further operation of the combination switch F and the secondary switch C takes place in the same manner as was described hereinbefore. 75

It will be noted that when ground is placed on the release trunk conductor 162 to start the secondary switch C that the relay 176 is short circuited. This is to prevent this relay from energizing in case ground is placed upon the starter wire 201 in order to start a secondary switch as a finder. Immediately upon the energization of the switching relay 178 the starter wire 201 is extended to an 80 idle secondary switch which is thereupon automatically operated, as before described, to find the seized trunk line. 85

The starting circuit for starting the secondary switches such as C and C' as finders 90 is an ordinary starting loop whereby a plurality of the switches may be started simultaneously. 95

The features of the invention having been described and ascertained, what is considered 100 to be new and desired to have protected by Letters Patent will be pointed out in the appended claims.

What I claim as my invention is:

1. In a telephone system, a telephone line, 105 a plurality of finder switches having access to said telephone line, a line switch linked with each of said finder switches, trunk lines accessible to said line switches, means controlled from said line for starting an 110 idle one of said finder switches to search for said line, and means operative whereby only an idle finder switch is started whose associated line switch has its wipers in engagement with an idle one of said trunk 115 lines.

2. In a telephone system, a group of finder switches, telephone lines accessible thereto, a secondary switch linked with each of said finder switches, trunk lines accessible to said 120 secondary switches, wipers for each of said secondary switches always standing in engagement with some one of said trunk lines, means for making some of said trunk lines busy, means controlled from one of said calling lines for starting an idle one of said 125 finder switches, and means for preventing the starting of this finder switch if its as-

sociated secondary switch has its switch wipers associated with a busy one of said trunk lines.

3. In a telephone system, a group of finder switches, telephone lines accessible thereto, a secondary switch linked with each finder of said group, trunk lines accessible to said secondary switches, means for making some of said trunk lines busy, each of said finder switches being normally first choice to a group of said telephone lines, means controlled from a calling one of said lines for starting the finder switch normally assigned to it if said switch is not in use, and means for preventing the calling line from starting said switch even if idle if its associated secondary switch is associated with a busy one of said trunk lines.

4. In a telephone system, a plurality of finder switches, a plurality of lines normally divided into groups for the purpose of starting said finders, there being a finder assigned to each group of lines, means whereby a calling line in any one of said groups can start the finder assigned to such group, a starting loop circuit for starting said finder switches whereby when one of said finders normally assigned to a group connects with a calling line in that group the starting circuit is extended to the next switch, a secondary switch linked with each finder switch, trunk lines accessible to said secondary switches, and means for extending said starting loop to the next finder each time the associated secondary switch is in engagement with a busy one of said trunk lines.

5. In a telephone system, a plurality of telephone lines arranged in groups, a plurality of finder switches having access to said lines, there being one of said finder switches normally assigned to each of said groups, a starter wire circuit to control the starting of the switch of a succeeding group if the finder assigned to the group in which the call originates is busy, means to extend the said starter wire to a succeeding switch when a calling line is seized, a secondary switch associated with each finder switch of said plurality, trunk lines accessible to said secondary switches, wipers for said secondary switches always associated with some one of said trunk lines, means for making any of said trunk lines busy, and means operative when the trunk line associated with one of said secondary switches becomes busy for extending the starter wire of the associated finder switch to the succeeding switch.

6. In a telephone system, telephone lines, automatic switches having access to said telephone lines, a secondary switch linked with each of said automatic switches, two groups of trunk lines accessible to said secondary switches, means controlled from a

calling one of said telephone lines for causing one of said automatic switches to operate as a finder to find said line, means operative to cause said secondary switch to seize one of said trunk lines, means operated by another calling subscriber for causing said secondary switch to find a trunk line used by the calling subscriber and for thereafter operating the associated automatic switch as a connector to extend a connection to one of said telephone lines.

7. In a telephone system, telephone lines divided into groups, finder switches having access to said telephone lines, a starting loop circuit whereby a plurality of finder switches may be started in search of a plurality of calling lines simultaneously means for extending the starter loop on as each switch becomes busy, secondary switches, trunk lines accessible to said secondary switches, wipers for said secondary switches always associated with one of said trunk lines, means for extending the starting loop to the next finder if the associated secondary switch has its wipers resting on a busy trunk line, and a second starting loop circuit which is controlled only by the finder switches becoming busy and which is independent of whether the associated secondary switches are standing on an idle trunk or not.

8. In a telephone system, telephone lines divided into groups, finder switches having access to said telephone lines, a starting loop circuit whereby a plurality of finder switches may be started in search of a plurality of calling lines simultaneously, means for extending the starting loop on as each switch becomes busy, secondary switches, trunk lines accessible to said secondary switches, wipers for said secondary switches always associated with one of said trunk lines, means for extending the starting loop to the next finder if the associated secondary switch has its wipers resting on a busy trunk line, a second starting loop circuit, which is controlled only by the finder switches becoming busy and which is independent of whether the associated secondary switches are standing on an idle trunk or not, and means effective when the first starting loop circuit is completely closed for switching the incoming starter wires onto said second loop circuit.

9. In a telephone system, telephone lines, a group of finder switches, a starting loop circuit whereby an idle one of said finder switches may be started from a calling one of said telephone lines, a secondary switch linked with each of said finder switches, trunk lines accessible to said secondary switches, a set of wipers for each of said secondary switches always associated with one of said trunk lines, means for making some of the said trunk lines busy, means operative when the wipers of one of said secondary

switches are associated with a busy trunk line for extending the starter loop in the associated finder switch on to the next finder, a second starter loop controlled only by the 5 said finder switches becoming busy, and means operative when said first loop is completed for bringing said second loop in to operative relation with said lines whereby a plurality of finder switches may be started 10 simultaneously over said second starting loop circuit.

10. In a telephone system, a two way link circuit having an automatic progressively movable switch at each end thereof, means 15 effective when a call is extended over said link in one direction for operating the switch at one end as a finder or backward selecting switch and the switch at the other end as a forward selecting switch, and means eff- 20 ective when a call is extended over said link in the other direction for operating the second switch as a finder or backward selecting switch while the first switch is operated as a forward selecting switch.

25. 11. In a telephone system, two way trunk line, two progressively movable switches at opposite ends of said trunk line and constituting the only terminals thereof, and means including said two switches for extending 30 connections over said trunk line in either direction.

35. 12. In a telephone system, a two way trunk line, two progressively movable automatic switches, one at each end of said trunk line, means including both of said switches for extending a connection over said trunk line in one direction, and means including the same two switches for extending a connection over said trunk line in the opposite 40 direction.

45. 13. In a telephone system, a two way trunk line, an automatic switch at each end of said trunk line, means for operating one switch as a backward selecting switch and the second switch as a forward selecting switch to extend a connection over said trunk line in one direction, and means for operating the said second switch as a backward selecting switch and the first switch as a forward selecting switch to extend a connection over 50 said trunk line in the opposite direction.

55. 14. In a telephone system, a telephone line, a group of combination switches having access to said line, an auxiliary switch individual to each combination switch, trunk lines accessible to said auxiliary switches, means controlled from said line for starting an idle one of said combination switches to search for said line, and means for starting the 60 first idle combination switch whose associated auxiliary switch is in engagement with an idle one of said trunk lines, providing at least one auxiliary switch is in engagement with an idle trunk line.

65. 15. In a telephone system, a telephone

line, a group of combination switches having access to said line, an auxiliary switch individual to each combination switch, trunk lines accessible to said auxiliary switches, means controlled from said line for starting an idle one of said combination switches to search for said line, and means for starting an idle combination switch whose associated auxiliary switch is in engagement with a busy one of said trunk lines providing no auxiliary switch is in engagement with an idle trunk line.

16. In a telephone system, a series of automatic switches for interconnecting calling and called lines, certain of said switches automatically operative to find the calling line and an idle trunk line respectively when used for outgoing calls, and directly and automatically operative to connect with terminals of a called line and of a busy 85 trunk line when used for incoming calls.

17. In a telephone system, a combination connector switch and finder switch, a combination line switch and finder switch, and a trunk line permanently linking said 90 switches together.

18. In a telephone system, a group of lines, link circuits for extending said lines when calling, each link comprising a line finder and a hunting switch, trunk lines accessible 95 to said hunting switches, means responsive to a call on one of said lines for starting an idle finder, and means for preventing any idle finder from starting responsive to a call unless its paired hunting switch is 100 standing on an idle one of said trunk lines.

19. In a telephone system, a group of lines, link circuits for extending said lines when calling, each link comprising a line finder and a hunting switch, trunk lines accessible 105 to said hunting switches, and means responsive to a call on one of said lines for starting the first one of said finders which has its paired hunting switch standing on an idle one of said trunk lines.

110. 20. In a telephone system, a switching device terminating a trunk line and having movable wipers, means for extending a telephone call through said switch over said trunk line in either direction, a condenser in 115 a talking conductor of said switch, means for including said condenser in the talking connection in a call in one direction, and means for excluding said condenser from the talking connection in a call in the other direction.

120. 21. In a telephone system, a switching device terminating a trunk line and having movable wipers, means for extending a call through said switch in either of two directions, means in said switch for supplying talking current to the calling and called subscribers when a call is extended through said switch in one direction, and means for disconnecting said current supplying means 130

- when a call is extended through said switch in the other direction.
22. In a telephone system, a combination finder and connector switch, means for supplying talking current to the called subscriber when said combination switch is used as a connector, and means for making said current supply means ineffective when said combination switch is used as a finder. 5
- 10 23. In a telephone system, telephone lines, an automatic switch having access to said telephone lines, trunk lines, an auxiliary switch permanently linked with said automatic switch having access to said trunk lines, means controlled from a calling one of said telephone lines for starting said automatic switch to operate as a finder to find said calling line and for causing said auxiliary switch to select an idle one of said 15
- 20 trunk lines, means operated by a second calling subscriber for starting said auxiliary switch to operate as a finder to find the trunk line used by said second calling subscriber and for operating said automatic switch as a connector to extend a connection to one of said telephone lines, and means for disabling the said second means when said automatic switch has been started as a finder. 25
24. In a telephone system, telephone lines, an automatic switch having access to said telephone lines, trunk lines, an auxiliary switch permanently linked with said automatic switch having access to said trunk lines, means controlled from a calling one of said telephone lines for starting said automatic switch to operate as a finder to find said calling line and for causing said auxiliary switch to select an idle one of said trunk lines, means operated by a second calling subscriber for starting said auxiliary switch to operate as a finder to find the trunk line used by said second calling subscriber and for operating said automatic switch as a connector to extend a connection to one of said telephone lines, and means for disabling the said first means when said auxiliary switch has been started as a finder. 40
- 45 25. In a telephone system, telephone lines, an automatic switch having access to said telephone lines, trunk lines, an auxiliary switch permanently linked with said automatic switch having access to said trunk lines, means controlled from a calling one of said telephone lines for starting said automatic switch to operate as a finder to find said calling line and for causing said auxiliary switch to select an idle one of said trunk lines, means operated by a second calling subscriber for starting said auxiliary switch to operate as a finder to find the trunk line used by said second calling subscriber and for operating said automatic switch as a connector to extend a connection to one of said telephone lines, and means for preventing either of said switches from being 50
- 55
- 60
- 65
- started as a finder while the other switch is in use as a finder.
26. In a telephone system, a combination line switch and finder switch terminating a link, trunk lines accessible to said combination switch, a starting circuit including a relay controlled over said trunk lines for starting said combination switch to operate as a finder, a second starting circuit controlled over said link for starting said switch to operate as a line switch, and means for short circuiting said relay when said switch is started as a line switch for preventing said switch from being started as a finder. 70
- 75
27. In a telephone system, a combination line switch and finder switch terminating a link, trunk lines accessible to said combination switch, a starting circuit including a relay controlled over said trunk lines for starting said combination switch to operate as a finder, a second starting circuit controlled over said link for starting said switch to operate as a line switch, and means for opening said second starting circuit when said switch is started as a finder for preventing said switch from being started as a line switch. 80
- 85
28. In a telephone system, a group of finders, a main starting circuit extending through said finders, an auxiliary starting circuit extending through said finders, two transfer relays in each finder, multiply connected contacts on each pair of relays included in said main starting circuit, and contacts on only one relay of each pair included in said auxiliary starting circuit. 90
- 95
29. In a telephone system, a group of finders, a main starting circuit extending through said finders, an auxiliary starting circuit extending through said finders, two transfer relays in each finder, multiply connected contacts on each pair of relays included in said main starting circuit, contacts on only one relay of each pair included in said auxiliary starting circuit, said auxiliary starting circuit being normally ineffective, a chain circuit including contacts on each pair of relays, and means controlled over said chain circuit for rendering said auxiliary starting circuit effective. 100
- 105
30. In a telephone system, a combination finder and connector switch having two test wipers, means including one of said wipers for testing a called line when said switch is used as a connector, and means including the other of said wipers for finding a calling line when said switch is used as a finder. 110
- 115
31. In a telephone system, a combination finder and connector switch having a connector test wiper normally in operative relation with said switch and a finder test wiper normally in inoperative relation with said switch, and means for substituting the second wiper for the first when said switch is used as a finder. 120
- 125
- 130

32. In a combination finder and connector switch, a combination testing and stepping relay for testing called lines and for finding calling lines.
33. In a combination finder and connector switch, a relay, a testing circuit for testing called lines and a second testing circuit for finding calling lines, both said circuits including said relay, busy signaling means controlled by said relay when the switch is used as a connector, and a stepping circuit controlled by said relay when the switch is used as a finder.
- 10 34. In a telephone system, a group of lines, a combination finder switch and con-

20 nector switch having access thereto, selector switches for use in completing calls outgoing from said group, selector bank terminals for use in completing calls incoming to said group, and free hunting non-numerical switching means for connecting said combination switch with one of said selectors to extend an outgoing connection, and for connecting said combination switch with said selector bank terminals to extend an incoming connection.

25 In witness whereof, I hereunto subscribe my name this 6th day of October, A. D., 1921.

JOHN E. GARDNER.
